UNITED STATES PATENT OFFICE.

ANITA M. BALDWIN, OF SANTA ANITA, CALIFORNIA.

DESIGN FOR A CUP.

48,809.

Specification for Design.

Patented Apr. 4, 1916.

Application filed July 19, 1915. Serial No. 40,782. Term of patent 14 years.

To all whom it may concern:

Be it known that I, ANITA M. BALDWIN, a citizen of the United States, residing in Santa Anita, county of Los Angeles, State of California, have invented a new, original, and ornamental Design for Cups, of which the following is a specification, reference being had to the accompanying drawing, forming part thereof, wherein—closing the base. Fig. 3 is a view in plan of the interior of the cup.

I claim:

The ornamental design for a cup, as shown.

In witness whereof I have signed my name to this specification in the presence of two witnesses.

ANITA M. BALDWIN.
